United States Patent Office

Des. 218,300
Patented Aug. 11, 1970

218,300

CHAIR

Bernard David Nightingale, 6 Wyegate Court,
Willowdale, Ontario, Canada

Filed Feb. 23, 1968, Ser. No. 10,697

Term of patent 14 years

Int. Cl. D6—01

U.S. Cl. D15—1

FIG. 2

FIG. 3

FIG. 1 is a front perspective view of a chair, showing my design,

FIG. 2 is a top plan view of the chair as shown in FIG. 1, and

FIG. 3 is a rear elevational view of the chair of FIGS. 1 and 2.

The dominant features of my design reside in those portions shown in full lines on the drawings.

I claim:

The ornamental design for a chair, as shown and described.
